UNITED STATES PATENT OFFICE

168,924

AIR CIRCULATOR

Robert H. Colvin, Delavan, Wis., assignor to The Gabriel Company, Cleveland, Ohio, a corporation of Ohio

Application October 11, 1951, Serial No. 16,912

Term of patent 14 years

(Cl. D62—4)

To all whom it may concern:

Be it known that I, Robert H. Colvin, a citizen of the United States, residing at Delavan, in the county of Walworth and State of Wisconsin, have invented a new, original, and ornamental Design for an Air Circulator, of which the following is a specification, reference being had to the accompanying drawing, forming part thereof.

In the drawing:

Fig. 1 is a perspective view of an air circulator embodying my new design;

Fig. 2 is a front elevational view thereof;

Fig. 3 is a back elevational view thereof; and

Fig. 4 is an end view thereof.

The characteristic features of the design reside in the portions shown in full lines.

I claim:

The ornamental design for an air circulator, substantially as shown and described.

ROBERT H. COLVIN.
